UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

CONVEYER.

Application filed April 17, 1922. Serial No. 554,284.

To all whom it may concern:

Be it known that RAY C. NEWHOUSE, a citizen of the United States, residing at Wauwatosa, in the county of Milwaukee and State of Wisconsin, has invented a certain new and useful Conveyer, of which the following is a specification.

This invention relates in general to improvements in the art of transporting or conveying substances, and relates more specifically to improvements in the construction and operation of automatic conveyers such as elevators for transferring material in bulk.

Generally stated, the object of the invention is to provide a conveyer which is simple in construction and efficient in operation.

It has been found in the construction of relatively long endless conveyers such as elevators adapted to automatically transport material from one elevation to another, that the driving or propelling chains must be constructed relatively heavy in order to secure sufficient strength to carry the loaded buckets. Such heavy construction of the chains limits the loads which may be transported by the elevator, and requires excessive power in order to operate the elevator when running idly. In endless elevators having extremely long stretches, the weight of the chain requisite to produce the necessary strength, requires the provision of relatively heavy driving gears and supporting structure for preventing sagging of the chain stretches, thereby inducing enormous friction losses and consequent waste of energy.

The present invention contemplates the provision of means for enabling the use of relatively light but sufficiently strong conveying elements in elevators having relatively great length, thus reducing to a minimum the cost of construction of such devices. The invention comprises the provision of one or more devices for supporting the weight of sections of the endless elevating chains and the buckets associated therewith, thereby relieving the driving mechanism of some of the load induced by the weight of these elements. It has been found that with the aid of the present invention, it is possible to employ the same propelling chains, sprockets and driving gears, that are ordinarily employed in devices adapted to carry

the same loads but which are at least 40% shorter from center to center of the end sprockets.

A clear conception of several embodiments of the present invention and of the operation of a device constructed in accordance therewith, may be had by referring to the drawing accompanying and forming a part of this specification, in which like reference characters designate the same or similar parts in the various views.

Fig. 1 is a fragmentary side elevation of an improved bucket elevator.

Fig. 2 is an enlarged central section through an improved intermediate support for endless bucket elevators.

Fig. 3 is an enlarged side view of the improved intermediate support for endless bucket elevators.

The elevator specifically illustrated in the drawing comprises in general a series of conveyor buckets or pans 2 supported by endless chains consisting of series of interconnected links 6, upper or head sprockets 4 rotatably supported in bearings secured to the upper stationary frame 26 by means of a sprocket shaft 25, lower or tail sprockets 3 coaxing with the links 6 and rotatably supported upon a floating tension carriage 10 by means of a sprocket shaft 27, intermediate sprockets 5 coaxing with medial portions of the endless chain stretches and rotatably and automatically adjustably supported from stationary frames 19, 20 by means of a sprocket shaft 18, and a feed hopper 12 for delivering material into the buckets or pans 2 as they pass in succession around the lower or tail sprocket 3.

The chain links 6 carry rollers 32 which coact with upper and lower stationary supporting rails 7, 8, 9 to prevent excessive sagging of the chain stretches due to loading of the buckets. The upper or head sprockets 4 are rotatable through gearing 23, by means of an electric motor 28 or other suitable driving device. A ratchet wheel 24 secured to the upper sprocket shaft 25 is normally engaged by a pawl release mechanism 21 which is operable to release a pawl 22 and to cause this pawl 22 to engage the teeth of the ratchet wheel 24, when reverse rotation of the shaft 25 from normal, tends to occur. The floating tension carriage 10 which supports the lower or tail sprockets 3

is movably supported upon stationary rails 11, thereby permitting automatic adjustment of the lower sprocket 3 to take up slack in the chain stretches.

- 5 One or both of the intermediate or equalizing sprockets 5 may be secured to the sprocket shaft 13 by means of keys 29, and have teeth meshing with both stretches of the elevator chains. The shaft 13 is freely 10 rotatably supported in bearings 14 confined between spaced guide-ways 18 and resting upon the upper extremities of nests of compression springs 15. The lower extremities of the springs 15 react against adjustable 15 plates or supports 16 which in turn rest upon the threaded adjusting rods 17. The threaded rods 17 coact with threaded plates or brackets 30 supported upon the stationary frame 19. The upper stretches of the elevator chain are preferably provided with 20 retaining rails or guards 31 for preventing the chains from leaving the upper teeth of the intermediate sprockets 5.

During normal operation of the elevator, 25 the upper driving sprockets 4 are being positively rotated in a clockwise direction as viewed in Fig. 1, by means of the motor 28 and the driving gearing 23. Rotation of the upper sprockets 4 causes the endless elevator 30 chains to move as indicated by the arrow, and to rotate the lower and the intermediate sprockets 3, 5. During advancement of the endless chains, the rollers 32 ride over the successive stationary guide rails 7, 8, 9 and 35 thus prevent excessive sagging of the chain stretches. Material may then be delivered by gravity or otherwise, from the feed hopper 12 into the successive pans or buckets 2 passing the delivery spout, and the upward- 40 advancing loaded buckets 2 carry the material thus delivered therein over the upper sprocket 4 where the material is eventually discharged by gravity as the successive buckets 2 are inverted. By virtue of the floating 45 carriage 10, the lower sprockets 3 will automatically take up slack in the stretches of the endless chains and will keep these stretches taut.

With the tension of the springs 15 properly adjusted, the intermediate sprockets 5 will automatically function to sustain a considerable portion of the weight of the buckets 2 and of the chain located below the engaged teeth of the sprocket 5, the balance 50 of the weight of these elements being sustained by the guide rails 7, 9. The upper or driving sprockets 4 are therefore required to sustain only a portion of the weight of the buckets 2 and of the chain located above 55 the sprockets 5, the balance of the weight of these elements being sustained by the stationary guide rails 8, 9. The proportion of the weight supported by the intermediate sprockets 5 may be readily varied by adjustment of the rods 17 to vary the tension of 60

the springs 15. The guard rails 31 serve to retain proper intermeshing between the sprockets 3 and the upper chain stretches.

It will thus be noted that by providing the intermediate equalizer sprockets 5 the weight of the propelling chain may be materially reduced without sacrificing necessary strength, thus preventing excessive weight upon the upper driving sprockets 4 and upon the guide rails 7, 8, 9 and reducing to a minimum the power required to operate the elevator idly. In excessively long elevators it may be desirable to utilize more than one set of equalizing sprockets 5, and it will be obvious that this may readily be done. The device may also be made automatically adjustable to properly support the weight of the elements by employing weights or other yielding means in place of the compression springs 15. The springs 15 besides being readily adjustable may be quickly removed for replacement, without removing the sprockets 5 and the elements associated therewith. It will also be obvious that the equalizing device is applicable to vertical elevators and to elevators disposed at inclinations other than illustrated.

It should be understood that it is not desired to limit the invention to the exact details of construction and of operation herein shown and described, for various modifications within the scope of the claims may occur to persons skilled in the art.

It is claimed and desired to secure by Letters Patent.

1. In an elevator, a series of interconnected conveying devices forming oppositely traveling stretches, means for imparting motion to said stretches, a rotary idler element engaging inner portions of both of said stretches intermediate their ends, and means coacting with outer portions of both of said stretches to positively retain said stretches in engagement with said element.

2. In an elevator, a series of interconnected conveying devices forming oppositely traveling stretches, means for imparting motion to said stretches, a rotary idler sprocket engaging inner portions of both of said stretches intermediate their ends, and a stationary member coacting with the outer portion of each of said stretches adjacent to said sprocket to positively retain said stretches in engagement with said sprocket.

3. In an elevator, a series of interconnected conveying devices forming oppositely traveling rectilinear stretches, means associated with adjacent ends of said stretches for imparting motion thereto, means movable parallel to said stretches and engaging their opposite ends for maintaining said stretches taut, a rotary idler element engaging portions of both of said stretches intermediate their ends, and means coacting with both of said stretches adjacent to said idler

for positively retaining said stretches in engagement with said idler.

4. In an elevator, a series of interconnected conveying devices forming oppositely traveling parallel inclined rectilineal stretches, means associated with the upper ends of said stretches for imparting motion thereto, means movable along an inclined plane parallel to said stretches and coacting with their lower ends for maintaining said stretches taut, a rotary idler element engaging portions of both of said stretches intermediate their ends, and means coacting with both of said stretches adjacent to said idler for positively retaining said stretches in engagement with said idler.
5. In an elevator, a series of interconnect-

ed conveying devices forming oppositely traveling parallel inclined rectilineal stretches, means associated with the upper ends of said stretches for imparting motion thereto, means movable along an inclined plane parallel to said stretches and coacting with their lower ends for maintaining said stretches taut, a rotary idler element engaging inner medial portions of both of said stretches, and stationary means coacting with outer medial portions of both of said stretches to retain said stretches in engagement with said element.

In testimony whereof, the signature of the inventor is affixed hereto.

RAY C. NEWHOUSE.
